UNITED STATES PATENT OFFICE.

JOHN BERG, OF NEW YORK, N. Y.

VENTILATING SYSTEM.

1,119,921.

Specification of Letters Patent. Patented Dec. 8, 1914.

Application filed June 16, 1913. Serial No. 773,961.

To all whom it may concern:

Be it known that I, JOHN BERG, a citizen of Sweden, and resident of the borough of Manhattan, in the county of New York and State of New York, have invented certain new and useful Improvements in Ventilating Systems, of which the following is a specification.

This invention relates to an improved system for ventilating subways and tunnels.

The object of the invention is the production of a simple and effective system for ventilating subterranean railways by the movement of the cars or trains therein.

15 A particular object is to provide a system wherein each track is in a separate tunnel, which tunnel is divided between the stations into sections, wherein the air set in motion by the trains will be positively entrapped and expelled, and other air drawn in to take the place of the outgoing current.

Another particular object is to provide doors between the sections, which are operated by automatic devices to open the same 25 in advance of an approaching train and to close after the train has passed.

Still another object is to provide the doors with supplementary means operated directly by the trains themselves, which in case of 30 failure of the automatic devices open the doors without injury to the latter or to the trains.

Further objects and advantages will become apparent as the specification proceeds.

35 The advantages of the invention are best realized in a construction embodying partitions disposed obliquely across the tracks in each tunnel comparatively near the incoming ends of the stations. These partitions have doorways with doors to permit 40 the passage of the trains. Behind each partition, in the acute angle, is an exit duct, the oblique disposition of the partition and door serving to direct the air thereto. This oblique arrangement is preferably also taken 45 advantage of by hinging the doors so as to swing about a vertical axis, away from the train, and in the other acute angle. In this way the distance through which the doors 50 must swing is minimized. In addition there are the automatic devices, which may be of various kinds, for opening and closing the doors before and after the passage of the trains.

55 It will be apparent to those skilled in the art that the invention may be embodied in a

large number of specifically different constructions.

The accompanying drawings show one of these by way of illustration.

In the said drawings: Figure 1 is a horizontal section of the preferred construction; Fig. 2 is a cross-section on the line 2—2 of Fig. 1, looking in the direction of the arrow; and Fig. 3 is a fragmentary sectional elevation of Fig. 1, parts being omitted.

In these views the numeral 10 denotes one of the two tracks contained in a subway of which one of the walls is designated 11. A row of columns 12 is disposed between the tracks, and a corrugated iron partition 13 extends lengthwise of this row of columns so as to divide the subway into two separate tunnels, each with its track. A station platform is indicated at 14.

Means are provided for dividing each tunnel into non-communicating sections, preferably one section for each station, the division between sections being at a suitable distance from the approaching ends of the stations, so that the latter afford air entrances near the ends of the sections where the trains enter them. The divisions are afforded by oblique partitions 18, having doorways 19 adapted to be closed by doors 20. These doors in Figs. 1 to 3 are hinged at 21 so as to swing about a vertical axis, in one of the acute angles, away from an approaching train or car. In the other acute angle formed by each partition, and therefore behind the partition is a duct 23 leading to an outlet 24 for the air set in motion by the train. Means are provided for directing the air from the other side of the track over to this exit. To this end an inclined gutter-like air deflector 25 is disposed lengthwise at the side of the track, adjacent the center wall 12, leading upward to the top of the doorway. Here an extension 26 leads across over the doorway, into the exit, as at 27.

In this construction electrical means are provided for automatically operating the doors. As shown there are door opening and door closing circuits 30, 40 adapted to be closed, respectively, by switches 31, 41. The respective circuits contain solenoids 32, 42 adapted to act oppositely on a bar or core 33, which is connected with the door by a lever 34. The door opening circuit 30 also has a solenoid 35, the core 36 of which is connected to the switch 41 of the door closing circuit, to open or re-set said switch. In

like manner the door closing circuit 40 has solenoid means 45, 46 for re-setting the switch 31 of the door opening circuit. The switches 31, 41 are adapted to be closed 5 against contacts 37, 47 respectively, by a suitable projection 38 on the approaching car, the outline whereof is represented at 39 and its direction of movement being indicated by the arrow.

10 In operation, the approaching car closes the switch 31. This completes the door opening circuit 30, and thereby energizes the solenoids 32 and 35, of which the latter re-sets the switch 41 and the other moves the 15 bar 33 so as to open the door 20. The door stays open until the car or train has passed through and closes the switch 41. This action re-sets the switch 31 and energizes the door closing solenoid 42 so as to swing the 20 door shut. It will be understood that the switches 31, 41 may be located at any desired distance from the door.

Means are provided whereby the car opens the door by direct action in event of failure 25 of the regular automatic devices. In the particular construction shown, a rod 56 is pivoted at 57 to one of the columns or other suitable support, and projects obliquely across the track, being connected with the 30 door by means of rollers 58 at its end, which engage opposite sides of a bar 59 fixed to the door. If the door should not be opened in advance of the car, the latter will contact with the rod 56 so as to swing the door open. 35 Both the rod 56 and the bar 59 have sufficient resilience to cushion the impact, so that neither the door nor the car is injured. Thus it will be seen that the construction shown is an embodiment of yielding or cushioned linkage whereby the car opens the 40

door by direct action. When opened in this manner the door is swung far enough to engage an automatic catch 60, which locks the door open, and thus notifies the attendant on the platform that the regular mechanism is 45 out of order. Ordinarily the door is not swung far enough to engage this catch.

Having described my invention what I desire to secure by Letters Patent and claim is:—

50

1. In a ventilating system for subways, the combination of an oblique partition across the subway having a door opening for trains therethrough, an exit for vitiated air disposed in the acute angle formed by one of the subway walls and said oblique partition at the far side thereof with respect to the end of the station approached by the train, and means directing the air above the door into said exit.

55

2. In a ventilating system for subways, the combination of an oblique partition across the subway having a passage for trains therethrough, an opening for vitiated air disposed in the acute angle formed by 65 one of the subway walls and said oblique partition at the far side thereof with respect to the end of the station approached by the train, a deflector extending along the opposite wall of the subway, and an extension 70 conducting the air directed up said deflector over said passage into said opening.

Signed at the borough of Manhattan in the county of New York and State of New York this 14th day of June A. D. 1913.

JOHN BERG.
